R. G. LEDIG.
PEDAL FOR VELOCIPEDES, BICYCLES, &c.
APPLICATION FILED MAY 16, 1917.
1,254,610.

Patented Jan. 22, 1918.

UNITED STATES PATENT OFFICE.

RICHARD G. LEDIG, OF PHILADELPHIA, PENNSYLVANIA.

PEDAL FOR VELOCIPEDES, BICYCLES, &c.

1,254,610.

Specification of Letters Patent. Patented Jan. 22, 1918.

Application filed May 16, 1917. Serial No. 168,940.

To all whom it may concern:

Be it known that I, RICHARD G. LEDIG, a citizen of the United States, residing in the city and county of Philadelphia, State of Pennsylvania, have invented a new and useful Pedal for Velocipedes, Bicycles, &c., of which the following is a specification.

My invention consists in providing the pedal proper of the pedal of a velocipede, bicycle, etc., with ball bearings on the bolt on which said pedal proper is supported and by which it is connected with the crank arm of the velocipede, bicycle, etc., in a firm and durable manner.

The invention is satisfactorily illustrated in the accompanying drawing, but the important instrumentalities thereof may be varied, and so it is to be understood that the invention is not limited to the specific details shown and described, so long as they are within the spirit or scope of the claims.

Figure 1 represents a plan view of a pedal embodying my invention.

Fig. 2 represents a longitudinal section on an enlarged scale on line 2—2 Fig. 1.

Fig. 3 represents a side elevation of a detached member thereof.

Fig. 4 represents a partial side elevation of another detached member, and sections of adjacent portions.

Fig. 5 represents an elevation of a bolt employed.

Figs. 6 and 7 represent elevations of detached members of the pedal proper of the device.

Similar numerals of reference indicate corresponding parts in the figures.

Referring to the drawings:—

1 designates a bolt, one end of which is provided with a head having on its inner side the conical portion 2 which is surrounded by the cup 3, between which latter and the adjacent portion of the bolt 1 are interposed the balls 4, said cup having on its inner side the reduced neck 5 which freely encircles the adjacent portion of the bolt 1, the conical surface 2 of the head of the bolt, and the shoulder 6 of the cup 3 and neck 5 serving to retain said balls 4 laterally in position in the ball race formed by the said members.

7 designates a barrel which freely encircles the main portion of the bolt, and 8 designates a cup which is formed with a reduced neck 9 which latter freely encir-

cles the adjacent portion of the bolt 1, it being noticed as in Fig. 2 that the end portions of the barrel 7 are fitted tightly on the necks 9 and 5 of the respective cups.

10 designates the pedal proper of the device, the same consisting of a U-shaped plate composed of the side pieces 11 which extend parallel with the barrel 11 and front bend 12 joining said pieces 11. Connected with the latter are the cross plates 13 which have 65 openings 14 centrally therein so as to fit over the necks 5 and 9 of the cups 4 and 8 respectively.

On the bolt opposite to the head 2 is the tubular plug 15 which has a conical inner 70 end 16, the latter partly entering the cup 8 and forming with the same a ball race which receives the balls 17 which are adapted to roll on the adjacent portion of the bolt 1, it being noticed that the conical end of the 75 plug and the shoulder 21 formed by the cup 8 and the reduced neck 9 thereof retain the balls 17 laterally in position.

On the outer terminal of the bolt is the threaded stub 18 to which the crank arm 80 19 of the velocipede is secured in any suitable manner. It will be noticed that the terminal portion of the bolt 1 passes through said stub 18 and has its end riveted on the adjacent end of said stub as a head 20 which 85 overlaps the bore of said stub, thus firmly connecting said bolt with said plug and the other parts of the device, and preventing the bolt from displacement.

The plug 15 is properly spaced on the bolt 90 by means of the engaging shoulders 22 and 23 respectively on said bolt and the bore of the plug, the effect of which is evident.

It will be noticed that the cups have ball bearings respectively on the conical surface 95 3 of the bolt 1, and on the conical end 16 of the plug 15, and so the barrel 7 has indirectly ball bearings on the bolt, rendering the pedal proper 10 of the pedal to rock with but little friction, and consequently with 100 greatest freedom on the bolt.

The surface of the main body portion of the plug 15 is made polygonal as at 24, whereby it may be properly engaged by a wrench or other implement, so that the plug 105 may be turned conveniently in screwing it into the proper part of the crank arm 19, or for removing it therefrom, and the terminal of said body adjacent to the threaded stub 18 has thereon the shoulder 25 against 110

which the side of the contiguous portion of the arm 19 abuts, so as to form a tight joint therewith.

The parts or members of the device are 5 easily assembled, and when the bolt is driven home which may be through the opening in the bend 12 of the pedal proper, the end of said bolt at the outer terminal of the stub of the plug 15 is riveted or headed on said 10 terminal as at 20, and so the plug is fixed to the bolt, and the latter retained in its operative position, the device then being made up in its entirety as a compact, firmly united, inexpensive, strong and durable structure.

15 Having thus described my invention what I claim as new and desire to secure by Letters Patent, is:—

1. In a pedal for a bicycle or the like, a bolt-like member, a pedal proper rotatably 20 mounted thereon, a tubular plug having a stub, said bolt being passed through the bores of said stub and plug, the terminal portion of said bolt being secured on the outer end of said stub.

25 2. In a pedal for a bicycle or the like, a bolt-like member, a pedal proper rotatably mounted thereon, a tubular plug having a stub, said bolt being passed through the bores of said stub and plug, the terminal 30 portion of said bolt being secured on the outer end of said stub, and means on said bolt and plug serving to space the latter.

3. In a pedal for a bicycle or the like, a bolt-like member, a pedal proper rotatably 35 mounted thereon, a tubular plug having a stub, said bolt being passed through the bores of said stub and plug, the terminal portion of said bolt being secured on the outer end of said stub, said bolt having a 40 shoulder and the plug having an interior shoulder coöperating therewith to space the plug to prevent cramping of balls engaged by the inner end of the plug.

4. In a pedal for a bicycle or the like, 45 a bolt-like member, a pedal proper rotatably mounted thereon, a tubular plug having a stub, said bolt being passed through the bores of said stub and plug, the terminal portion of said bolt being secured on the outer end of said stub, said bolt having a 50 shoulder and the plug having an interior shoulder coöperating therewith to space the latter to prevent cramping of balls engaged by the inner end of the plug, and a cup 55 having a reduced neck freely encircling the bolt and forming with the adjacent end of the plug a ball-race.

5. In a pedal for a bicycle or the like, a 60 foot-piece, a bolt-like member on which said piece is rotatably mounted, a cup, and a tubular plug on said member, and means on said plug for connecting it with a crank arm member of said bicycle, the body of said plug having a wrench attaching surface.

6. A pedal proper, a headed bolt on which 65 said pedal proper is rotatably mounted, a tubular plug having thereon a shouldered stub adapted to support a crank arm of the device, said arm being secured on said stub, said plug being adapted to receive the end 70 portion of said bolt, cups surrounding said bolt and adapted to form with the head of the bolt and said plug ball races respectively, and a barrel surrounding said bolt and engaging said cups.

7. A pedal proper, a headed bolt on which the pedal proper is rotatably mounted, a barrel adapted to encircle said bolt, cups with which said barrel is connected, a tubular plug through which the end portion of 80 said bolt is passed, said plug having thereon a tubular stub through which the terminal portion of said bolt is passed, said stub being adapted to carry a crank arm of the velocipede, one of said cups and the head of 85 the bolt, and the other cup and said plug forming ball-races respectively, the terminal of said bolt being secured to the terminal of said stub.

8. A pedal proper, a headed bolt on which 90 the pedal proper is rotatably mounted, a barrel adapted to encircle said bolt, cups with which said barrel is connected, a tubular plug through which the threaded end of said bolt is passed, said plug having thereon 95 a tubular stub through which the terminal portion of said bolt is passed, said stub being adapted to carry a crank arm of the velocipede, one of said cups and the head of the bolt, and the other cup and said plug 100 forming ball races respectively, the terminal of said bolt having a securing head which overlaps the bore of said stub.

9. A pedal proper, a bolt, the same having a conical head, a cup with a reduced neck 105 freely encircling the adjacent portion of said bolt, said cup and head forming a race with balls therein, a cup with a reduced neck freely encircling the shank of said bolt opposite to said head, a tubular plug on an adjacent portion of said bolt, the same having on its inner end a conical surface forming with said last named cup a race with balls therein, a barrel adapted to encircle said bolt and having its ends connected firmly with the 110 necks of the aforesaid cups, said plug having on its outer portion a stub on which latter a crank arm of the velocipede is adapted to be secured, said bolt passing through said plug and stub and being secured to the latter.

10. A pedal proper, a headed bolt on which the pedal proper is rotatably mounted, a barrel adapted to encircle said bolt, cups with which said barrel is connected, a tubular plug through which the end of said bolt is passed, said plug having thereon a tubular stub through which the

terminal portion of said bolt is passed, said stub being adapted to carry a crank arm of the velocipede, one of said cups and the head of the bolt, and the other cup and said plug forming ball-races respectively, the terminal of said bolt being secured to the terminal of said stub, the bore of said plug and the adjacent portion of the bolt having thereon abutting shoulders adapted to space said ball races.
